US0D1105022S

(12) **United States Design Patent** (10) **Patent No.:** **US D1,105,022 S**
(45) **Date of Patent:** **** Dec. 9, 2025**

(54) **TELEVISION RECEIVER**

(71) Applicant: **LG DISPLAY CO., LTD.**, Seoul (KR)

(72) Inventors: **Sunghyun Heo**, Paju-si (KR); **Jaehan Kim**, Paju-si (KR); **Sangyoon Byun**, Paju-si (KR); **Lisie Park**, Paju-si (KR); **Hongseok Seo**, Paju-si (KR); **Minkwan Seo**, Paju-si (KR)

(73) Assignee: **LG DISPLAY CO., LTD.**, Seoul (KR)

(**) Term: **15 Years**

(21) Appl. No.: **29/942,195**

(22) Filed: **May 14, 2024**

Related U.S. Application Data

(63) Continuation of application No. 35/516,552, filed on May 6, 2022 (U.S. filing date under 35 U.S.C. 384), and having an international filing date of May 6, 2022, now Pat. No. Des. 1,031,681.

(30) **Foreign Application Priority Data**

(57) **CLAIM**

The ornamental design for a television receiver as shown and described.

DESCRIPTION

FIG. 1 is a front, right, top perspective view of a television receiver showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the television receiver that form no part of the claimed design.

1 Claim, 7 Drawing Sheets
